UNITED STATES PATENT OFFICE.

HENRY T. SCHIFF, OF CHICAGO, ILLINOIS, ASSIGNOR TO FAY MANUFACTURING CO.,
OF CHICAGO, ILLINOIS, A CORPORATION OF ILLINOIS.

DESIGN FOR AN AUTOMATIC LIGHTER OR SIMILAR ARTICLE.

Application filed December 5, 1928. Serial No. 29,126. Term of patent 14 years.

To all whom it may concern:

Be it known that I, HENRY T. SCHIFF, a citizen of the United States, and residing in the city of Chicago, in the county of Cook and State of Illinois, have invented a new, original, and ornamental Design for an Automatic Lighter or Similar Article, of which the following is the specification, reference being had to the accompanying drawings, forming a part thereof.

On the drawings:

The figure is a perspective view of an automatic lighter or similar article showing my new design.

I claim:

The ornamental design for an automatic lighter or similar article as shown.

HENRY T. SCHIFF.
